UNITED STATES PATENT OFFICE

134,943

DESIGN FOR A BUMPER BAR OR THE LIKE

Merlin Mitchell, Orlando, Fla.

Application November 7, 1942, Serial No. 108,716

Term of patent 7 years

To all whom it may concern:

Be it known that I, Merlin Mitchell, a citizen of the United States, residing at Orlando, in the county of Orange and State of Florida, have invented a new, original, and ornamental Design for a Bumper Bar or the like, of which the following is a specification, reference being had to the accompanying drawing, forming part thereof.

In the drawing:

I claim:

The ornamental design for a bumper bar or the like, as shown and described.

MERLIN MITCHELL.
